UNITED STATES PATENT OFFICE.

ALBERT E. LYCAN, OF EUREKA, ILLINOIS.

SWINGING GATE.

SPECIFICATION forming part of Letters Patent No. 559,141, dated April 28, 1896.

Application filed June 26, 1895. Serial No. 554,107. (No model.)

To all whom it may concern:

Be it known that I, ALBERT E. LYCAN, a citizen of the United States, residing at Eureka, in the county of Woodford and State 5 of Illinois, have invented a new and useful Swinging Gate, of which the following is a specification.

This invention relates to gravity-closing gates which are adapted to be opened and 10 closed from either approach and which are held in either an open or a closed position by positive means or catches, the latter being released by the same means employed for opening and closing the gate.

15 The objects in view are to provide a gate which can be easily opened against the strongest wind, to obviate the use of a great number of castings, which are easily broken in cold weather, to simplify the construction 20 and reduce the operating parts to a minimum number, and to provide a gate which will be durable and capable of withstanding the rough usage to which devices of this character are subjected.

25 Other objects and advantages will become apparent as the nature and construction of the invention are understood from the following description and the accompanying drawings, in which—

30 Figure 1 is a perspective view of a gate embodying the invention, showing it open. Fig. 2 is a side elevation of the gate, showing it closed. Fig. 3 is a detail view of the main catch.

35 The gate comprises a series of longitudinal bars 1, front and rear battens 2 and 3, a diagonal brace 4, a vertical stay 5, and longitudinal barb wires 6, which are firmly attached at their ends to the battens and intermediate 40 of their ends to the brace 4 and stay 5 at the points of crossing. A post 7 is placed at one side of the roadway, and the gate is hinged thereto in such a manner that its outer end will rise when opening, thereby throwing the 45 weight to one side of a line passing vertically through either the upper or the lower hinge, so that when the gate is released after being opened it will close automatically by the force of gravity, as will be readily appreciated.

50 The knuckle of the upper hinge 8 is at a greater distance from the inner face of the post 7 than the knuckle of the lower hinge

9, thereby throwing the axial line of rotation of the gate out of a perpendicular line, which results in the automatic closing of the gate 55 in the manner aforesaid. A latch-post 10 occurs at the opposite side of the roadway and is supplied on its inner side with a double catch 11 and with a double inclined latch-raiser 12. The gate when closed extends between the posts 7 and 10 and is held fast by the engagement of its latch-bar 13 with the catch 11, the latter having a recess in its bottom edge to engage with the active or projecting end of the latch. 60

The latch-bar 13 is pivoted about midway of its ends upon a bolt or pivot 14, passing transversely through the diagonal brace 4, and is limited in its movements by blocks 15, secured to the rear batten 3, between which 70 the rear end of the said latch-bar 13 operates. A coil-spring 16 is secured at one end to the latch-bar and at its opposite end to the batten 3 and exerts a downward pull upon the rear end of the latch-bar 13 and holds it in 75 engagement with the lower stop 15, and this spring is located between the parallel bars comprising the batten 3 and is protected thereby and hidden from view.

A roller 17 is secured upon the front side 80 of the batten 2 a short distance above the front end of the latch-bar 13 and is designed to travel upon the top side of the double catch 11, so as to steady and prevent sagging of the outer end of the gate when closed. The 85 upper side of the double catch 11 is slightly inclined in opposite directions from a middle point, so as to receive the roller 17 and give a proper position to the gate when the latter is closed. Thus should the gate sag appreciably at its free end, it will be elevated by the rollers engaging the outer lower end of the catch 11 and riding upon the upper inclined side, as will be readily understood. 90

The double inclined latch-raiser 12 is intended to cause positive engagement of the latch-bar with the catch 11 should the spring 16 through any cause fail to operate. 95

Posts 18 are set on the same side of the roadway with the post 7 and on opposite sides of the latter and at nearly equal distances therefrom, and incline slightly from the perpendicular toward the roadway, and these posts have catches 19 and latch-raisers 20 to coöp-

erate with the catches 19 in a similar manner to the latch-raiser 12. Arms 21 are secured at their inner ends to the posts 18 and incline upwardly and forwardly, so as to overhang 5 the roadway, and are provided at their upper ends with pulleys 22, over which pass operating cords or ropes 23, by means of which the latch-bar is released and the gate opened and closed. A bar 24 inclines to the gate and ex- 10 tends in the rear thereof and is firmly attached at its lower end to the diagonal brace 4 and between its ends to the upper corner of the rear batten 3, and, if desired, to the longitudinal bars 1 at the points of crossing there- 15 with. A pulley 25 is located at the upper end of the bar 24, and the operating cords or ropes 23 pass thereover and are connected at their lower ends to the inner portion of the latch- 20 bar 13, so that by pulling upon either cord or rope 23 the latch-bar will be disengaged from the catch with which it is engaged, and a continued pull upon the said rope or cord will result in an opening or closing of the gate, according to the position which the latter may 25 occupy when the cord or rope is pulled upon. To facilitate the grasping of the ropes or cords 23, they are supplied at their pendent ends with handles 26 of any desired pattern.

From what has been said it will be seen 30 that the gate is substantially braced and comprises a minimum number of parts consistent with strength and durability, and that the single oblique bar 24 provides ample leverage for the successful manipulation of the gate 35 when it is required to open and close the same, and the overhanging arms 21 admit of the handles 26 extending within convenient reach

from the roadway. For different locations the style and pattern of the gate will be made to conform to the particular need and design. 40 Therefore in the adapting of the invention to meet the special requirement it is to be understood that various changes in the form, proportion, and the minor details of construction may be resorted to without departing 45 from the principle or sacrificing any of the advantages of this invention.

Having thus described the invention, what is claimed as new is—

In combination, a gravity-closing gate, a 50 longitudinally-disposed latch-bar, stops disposed to limit the movements of the latch-bar, a housed spring for holding the latch-bar in operative relation, a roller located above the operating end of the latch-bar, a 55 double catch having its top side oppositely inclined, a latch-raiser beneath the said catch, posts 18 arranged on the same side of the roadway with the post to which the gate is hinged, and having catches and latch-raisers, arms 60 secured to the posts 18, an obliquely-disposed bar bracingly attached to the gate and extending in the rear thereof, and operating cords or ropes passing over pulleys at the ends of the oblique bar and arms, and having con- 65 nection with the said latch-bar, substantially as set forth for the purpose described.

In testimony that I claim the foregoing as my own I have hereto affixed my signature in the presence of two witnesses.

ALBERT E. LYCAN.
